CONTROL APPARATUS

Joseph Harrington, Jr., Wenham, Mass., assignor
to United Shoe Machinery Corporation, Flem-
ington, N. J., a corporation of New Jersey

Application August 14, 1947, Serial No. 768,552

3 Claims. (Cl. 74—198)

1

This invention relates to control apparatus and particularly to apparatus for controlling the training movements of a device such, for example, as a telescope, gun, searchlight etc.

In the training of devices, such as those just mentioned, it is a common practice to provide a control handle which is adapted to be grasped by the hands of an operator and moved by him to control the movements of the device in azimuth and in elevation. However, when the extent of such training movements in azimuth or elevation becomes considerable and the necessary displacement of the control handle correspondingly increased, it is extremely awkward for the operator to twist his hands and wrists far enough to accomplish the desired movement of the device or, at least, impossible for him accurately to control its movements. This is particularly true where the device is being trained to follow the path of a moving aircraft which may require a complete rotation of the device in azimuth and a very great angular movement thereof in elevation.

It is, therefore, an object of this invention to provide an improved control apparatus by means of which even the most extensive training movements of a device may be controlled with the greatest of ease and accuracy. To this end, the herein illustrated control apparatus is provided with a control member which, regardless of its position, always presents the same surface for engagement by the hands of the operator. More particularly, this control apparatus comprises a device mounted for swinging movement about two transverse axes, i. e., training, training movement in azimuth and elevation, separate power-operated means for moving the device about each axis and a spherical member which is mounted for universal rotation and arranged to control the movements of the device. As herein illustrated, the means for moving the device include two friction wheels, one mounted for rotation in a horizontal plane, for controlling the movements of the device in azimuth, and the other mounted for rotation in a vertical plane, for controlling the movements of the device in elevation, while the spherical member is supported for universal rotation and in frictional engagement with the aforementioned wheels. With this arrangement, the spherical member may be rotated by the operator in any direction in which it is desired to move the device and, inasmuch as the horizontal and vertical components of the rotation of this member are picked up by the two friction wheels, the movements of the device will thereby be

determined. Also, as the extent of movement in any direction increases, the operator merely re-engages his hands with a different portion of the surface of the spherical member, thus avoiding the necessity for assuming an awkward position as well as the resulting inaccuracy of control.

The above, and other, objects and features of the invention will appear in the following detailed description of the embodiment illustrated in the accompanying drawings, and will be pointed out in the claims.

In the drawings,

Fig. 1 is a view in side elevation of a control apparatus embodying the features of this invention;

Fig. 2 is a view, in perspective and with certain parts broken away, of a portion of the apparatus shown in Fig. 1;

Fig. 3 is a schematic view of the operating mechanism of the apparatus; and

Fig. 4 is a plan view, at a reduced scale, of a portion of the apparatus.

Referring to Fig. 1 of the drawings, the device which is to be controlled is illustrated as being a telescope 10, shown mounted on the top of a hollow standard 12 which is supported on a fabricated frame 14. This frame comprises a top plate 18, carried by a plurality of columns 20 which extend upwardly from a base 22. The mechanism for operating the telescope, under the control of a spherical member 16, is contained within a box 24 which is secured to the top plate, directly beneath the standard 12, and includes two friction wheels 26 and 28, the former being mounted for rotation in a horizontal plane and the latter for rotation in a vertical plane.

The spherical member 16 is supported for universal rotation on a ball bearing 30 which rides on a plurality of rollers 32, 32, carried by a block 34, and this block is secured on the base 22. A bracket 36 extends rearwardly from the frame 14, above this spherical member 16, and is provided with two plungers 38, 38, arranged to engage the surface of the spherical member, rearwardly of the ball bearing 30 and on the opposite sides of a diametrical plane passing through the ball bearing 30 and between the friction wheels 26, 28, see Fig. 4. These plungers are backed up by coil springs 40, 40, the tension of which will be varied by means of screws 42, 42. With the arrangement just described, the spherical member 16 is urged yieldingly, against the friction wheels 26 and 28 while still being free for rotation in any direction. As will be ap-

parent, the vertical component of the rotation of the spherical member 16 will be transmitted to the roll 28, which rotates in a vertical plane, while the horizontal component thereof will be transmitted to the roll 26 which rotates in a horizontal plane. The rotation of these friction wheels is imparted to the telescope 10 by means of mechanism about to be described.

Referring to Fig. 2 of the drawings, the telescope 10 is mounted in a sleeve 50 which is provided with an arm 52, secured to one end of a shaft 54. This shaft is journaled in a bearing 56, formed in a bracket 55 that extends upwardly from a disk 58 which is rotatably mounted on the top of the hollow standard 12 by means of three rollers, one of which is visible in Fig. 2 and indicated by the reference character 60. Secured to the other end of the shaft 54, is a spur gear 62 which is in mesh with a rack bar 64 that is slidably supported on a guide boss 66 on the disk 58. A shaft 68 is fixed to the disk 58 and extends downwardly, through the hollow standard 12, and into the box 24. The rack bar 64 likewise extends downwardly into the standard 12 and, at its lower end, is connected, by means of a link 70, to a yoke 72 which is slidable on the shaft 68, and splined thereto by means of a key 74. The yoke 72 has an annular groove 76 in which the trunnion pin 78 of a block 80 rides. This block has two feet 82, 84, which bear against the inside wall of the hollow standard 12 and is secured to a second rack bar 86 that extends downwardly into the box 24.

Rotation of the shaft 74 is transmitted directly to the telescope 10, so as to swing it in azimuth, while the vertical movement of the rack bar 86 is transmitted, through the block 80, yoke 72, link 70, rack bar 64 and spur gear 62, to the telescope, to move it in elevation. As will presently appear, the friction wheel 26, which is rotated in accordance with the horizontal component of rotation of the spherical member 16, is connected to the shaft 68; while the friction wheel 28, which is rotated in accordance with the vertical component of rotation of the spherical member 16, is connected to the rack bar 86. Thus the movements of the spherical member 16 are imparted to the telescope 10. The herein illustrated mechanism for moving the telescope is adapted to provide a so-called "aided tracking" control; that is to say, rotation of the spherical control member 16, in any given direction in elevation, azimuth, or a combination of both, and for a predetermined amount, will not only result in angular movement of the telescope 10, in the same direction and to the same extent, but also will establish a rate of angular movement of the telescope in that direction which is proportional to the initial displacement of the spherical member.

Referring now to Fig. 3 of the drawings, and considering first the movement of the telescope in azimuth, which as already indicated is controlled by the rotation of the friction wheel 26, the shaft 68 is connected to the output shaft 100 of a differential having two input gears 102, 104 and a cage 105. The input gear 104 is rotated directly by the friction wheel 26 through shafts 106, 107, 108 and gears 110, 112, 114, 116, 118 and 120. The input gear 102 is connected, by gears 122, 124 and 126 and shaft 128, to the output cylinder 130 of a variable speed drive comprising a disk 132, balls 134 and ball carriage 136. This ball carriage is adjustable, to displace the balls 134 relatively to the center of the disk 132, by means of a pinion 138 carried by a shaft 140

which is normally connected to the shaft 107 by means of a friction clutch 142. The disk 132 is driven at a constant speed by a motor 144, through gears 146, 148 and a shaft 150.

Assuming that the telescope is in a "zero" position in azimuth, as shown in Fig. 3, the balls 134 will be in the center of the disk 132 and the input gears 102 and 104 will be stationary as will, of course, the cage 105 and the output shaft 100. Now, if the spherical member is rotated "a" degrees in azimuth this rotation will be transmitted to the friction wheel 26 and the following movement of the telescope 10 will result. First, the arrangement of the gearing comprising gears 104, 110, 112, 114, 116, 118 and 120 is such that the telescope will be moved "a" degrees in the same direction as the spherical member was displaced. This provides the "space" component of the "aided tracking" action.

However, the rotation of the friction wheel 26 will also rotate the shaft 140 which, through the pinion 138, will effect a displacement of the balls 134 from the center of the disk 132. Therefore, the input gear 102 will now be rotated at a speed which is proportional to the displacement of the spherical member 16. The direction of rotation of the disk 132 and the arrangement of the gearing comprising gears 122, 124 and 126 is such that the cage 105 and the output shaft 100 will be rotated in the same direction as the spherical member 16. Accordingly, the telescope 10 will continue to move in the direction in which the spherical member 16 was originally displaced and at a "rate" which is proportional to the amount of the displacement of the spherical member. This provides the "rate" component of the "aided tracking" action.

Now, if it is desired to change the rate of movement of the telescope, the spherical member must be displaced in the proper direction, i. e., reversely to slow down the rate and forwardly to increase it, it being noted that, in either case, the telescope will be moved, reversely or forwardly, an angular distance equal to this displacement of the spherical member by the direct (space) control through input gear 104. In order to stop the movement of the telescope, the spherical member must be displaced reversely until the balls 134 are restored to their original position in the center of the disk 132. As will be apparent, by appropriately manipulating the spherical member to displace it in the desired direction, and to the proper amount, in azimuth, the operator can control the movement of the telescope, increasing its speed, decreasing its speed, or bringing it to a stop as desired.

The same kind of action is obtained when the spherical member is rotated in elevation to effect rotation of the friction wheel 28. The rack bar 86, the vertical movement of which swings the telescope in elevation, is in mesh with a gear 199 on a shaft 201 which is connected, through a slip-clutch 400, to the output shaft 200 of a differential having two input gears 202 and 204, and a cage 205. The input gear 204 is rotated directly by the friction wheel 28, through shafts 206, 207, 208 and gears 210, 212, 214, 216 and 218. In order to assure a good frictional contact of the friction wheels 26, 28 with the surface of the spherical member 16, the shaft 106 is journaled in a bearing, not shown, provided in a fixed portion of the box 24, while the shaft 206 is carried by an arm 300 that is pivotally mounted on a fixed shaft 302. The pivotal movement of this arm is limited, to the

extent permitted by a slight amount of play between the gears 210 and 212, by means of stop screws 304, 306, and a coil spring 308 is arranged to swing the arm 300 in a direction to hold the wheel 28 in contact with the surface of the spherical member 16 which is held yieldingly in contact with the friction wheel 26 by the action of the plungers 38, 38.

The input gear 202 is connected, by means of gears 222, 224, 226 and a shaft 228, to the output cylinder 230 of a variable speed drive including a disk 232 and a ball carriage 236, carrying two balls, not shown, but similar to the two balls 134 of the variable speed drive which has been described above. This ball carriage is adjustable, to displace the two balls relatively to the center of the disk 232, by means of a pinion 238 carried by a shaft 240 which is normally connected to the shaft 207 by means of a friction clutch 242. The disk 232 is driven at a constant speed by the motor 144 through gears 244, 246, 248 and a shaft 250.

The operation of this mechanism to move the telescope in elevation is the same as has just been described in connection with the control of the movements of the telescope 10 in azimuth and, by appropriately manipulating the spherical member 16 to displace it in the desired direction and to the proper extent, in elevation, the operator can control the movements of the telescope, increasing its speed, decreasing its speed, or bringing it to a stop as desired. Compound movements of the telescope, to train it simultaneously in azimuth and elevation, are obtained by rotating the spherical member in a direction corresponding to that in which it is desired to have the telescope moved. For example, if the operator wishes to move the telescope upwardly, and to his right, he would grasp the spherical member with both of his hands, as is indicated at *h* in Fig. 1, and rotate it in the same direction in which the telescope is to be moved.

Such movement of the spherical member can be resolved into two components, one parallel to a vertical plane passing through the center of the spherical member and the friction wheel 28 and another parallel to a horizontal plane passing through the center of the spherical member and the friction wheel 26. The first of these components will be transmitted to the friction wheel 28 and, in accordance with the direction and extent thereof, will effect movement of the telescope in elevation as has already been explained. Similarly, the second component will be transmitted to the friction wheel 26 and, in accordance with the direction and extent of this component will effect movement of the telescope in azimuth. When the extent of displacement of the spherical member, necessary to produce a desired movement of the telescope, both with respect to the extent of movement as well as the speed of movement, becomes considerable, the operator merely re-engages his hands with a different portion of the surface of the spherical member and displaces it as required for the continued control of the movement of the telescope. Thus, it is not necessary for him to twist his hands or wrists excessively or to assume an awkward position. With his two hands in a natural position and in contact with the spherical member, the operator can have a very accurate and easy control over the displacement of the spherical member and of the movements of the telescope. As will be obvious, the operator can readily effect movement of the telescope through

360° in azimuth with no difficulty, and even the extreme limits of movement of the telescope in elevation impose no strain upon his hands.

It sometimes may be desirable to eliminate the "rate" control function of the control mechanism and to move the telescope solely from the spherical member 16 with a so-called "space" control. For this purpose, the friction clutches 142, 242, are provided, respectively, with yokes 342, 344 which are adapted to be shifted to release these clutches, thereby disconnecting the shafts 107—140 and 207—240, and eliminating the "rate" control feature provided by the variable speed drives. The yokes 342, 344 are provided, respectively, with operating arms 346, 348, arranged to be engaged by a pair of cams 350, 352, carried by a shaft 354. A crank arm 356 is secured to this shaft for rotating it to engage these cams with the yoke arms. In operating the device with this "space" control only, the spherical member 16 is first manipulated so as to position the balls of the two variable speed drives in centered position with respect to their disks and then the crank arm is turned in the direction of the arrow in Fig. 3, thereby disengaging the two friction clutches 142, 242. Now, as the two input gears 102 and 202 will be held stationary, the telescope 10 will follow the movements of the spherical member 16 as a result of the rotations of the friction wheels 26, 28 which are, respectively, fed into the two input gears 104 and 204 of the two differentials.

Having described my invention, what I claim as new and desire to secure by Letters Patent of the United States is:

1. A control apparatus having, in combination, a device mounted for training movements in azimuth and elevation, means for moving said device in azimuth, including a friction wheel mounted for rotation in a horizontal plane, means for moving said device in elevation, including a friction wheel mounted for rotation in a vertical plane, a spherical member, and means for supporting said spherical member for universal rotation with its surface in frictional contact with said friction wheels.

2. A control apparatus having, in combination, a device mounted for training movements in azimuth and elevation, power-operated means for moving said device in azimuth, including a friction wheel rotatable in a horizontal plane for controlling the speed and direction of movement of said device in azimuth, means for moving said device in elevation, including a friction wheel mounted for rotation in a vertical plane for controlling the speed and direction of movement of said device in elevation, a spherical member, and means for supporting said spherical member for universal rotation with its surface in frictional contact with said friction wheels.

3. A control apparatus having, in combination, a device mounted for training movement in azimuth and elevation, means for moving said device in azimuth comprising a differential having two inputs and an output, a power driven variable speed gear connected to one of said inputs and a friction wheel, rotatable in a horizontal plane, connected to the other of said inputs, means for moving said device in elevation comprising a second differential having two inputs and an output, a power driven variable speed drive connected to one of said inputs and a friction wheel, rotatable in a vertical plane, con-

nected to the other of said inputs, a spherical member, and means for supporting said spherical member for universal rotation with its surface in frictional contact with said friction wheels.
